UNITED STATES PATENT OFFICE.

JOHN B. BARNETT, OF FORT WORTH, TEXAS, ASSIGNOR TO J. I. CLINGMAN AND
A. D. HODGSON, BOTH OF FORT WORTH, TEXAS.

ADVERTISING-MACHINE.

1,256,645.

Specification of Letters Patent. Patented Feb. 19, 1918.

Application filed June 29, 1916. Serial No. 108,702.

To all whom it may concern:

Be it known that I, JOHN B. BARNETT, a citizen of the United States, residing at Fort Worth, in the county of Tarrant and State of Texas, have invented certain new and useful Improvements in Advertising-Machines, of which the following is a specification.

My invention relates to display advertising apparatus and more particularly an apparatus by which intermittent exposures are produced, and the object is to provide a simple advertising apparatus provided with means for changing the displays at predetermined times, and to provide means for operating the apparatus continuously and which will not be displaced in operation. Other objects and advantages will be fully explained in the following description and the invention be more particularly pointed out in the claims.

Reference is had to the accompanying drawings which form a part of this application.

Figure 1 is a front elevation of the machine with the casing cut away to expose the interior mechanism.

Fig. 2 is a horizontal section taken on the line $y-y$ of Fig. 1.

Fig. 3 is a vertical section taken on the line $z-z$ of Fig. 1.

Fig. 4 is a horizontal section taken on the line $x-x$ of Fig. 3.

Fig. 5 is an enlarged view, being a horizontal section, of one of the advertising slabs.

Similar characters of reference are used to indicate the same parts throughout the several views.

The machine is provided with a casing which incloses all of the parts except the advertising slabs. The casing 1 is mounted on a base 2 and a supporting frame 3 is attached to the base 2. A slab-holding frame 4 is attached to the frame 3 by brackets 25 and by the shafts 8 hereinafter described. A plurality of three-faced slabs 7 are provided with shafts 8 which are journaled in the quadrangular frame 4 and also in the base frame 3. The three-faced slabs have their faces equal on all sides and means are provided for rotating the advertising slabs intermittently. Each shaft 8 is provided with projecting arms 9 which form in effect a mutilated gear wheel. A shaft 10 may be

driven by any suitable power, as by an electric motor 12 which is provided with a shaft 24 for driving a worm-wheel 13, which meshes with and drives a worm-gear wheel 14 which is rigid with the shaft 15. The 60 shaft 15 is journaled in a bearing 21 carried by a bracket or standard 18, which is attached to the base 2. The shaft 15 carries and drives a pinion 16, which meshes with and drives a cog-wheel 17 which is rigid 65 with shaft 10. The shaft 10 is provided with mutilated gear-wheels 11. The gear-wheels 11 drive the mutilated gear-wheels 9 and thus rotate the shafts 8 and the advertising slabs. The gear wheels 10 are preferably provided with four arms which make the mutilated gear, and the mutilated gear 9 consists of three arms corresponding to the three sides of the advertising slabs. It is apparent that there could be more faces to 70 the slabs and more arms making up the gear wheels 9 and 11. Means are provided for holding the faces of the slabs 7 in uniform positions, that is, with the flat faces all presented to view. Three-sided holding 80 blocks 23 are mounted on the shafts 8 and bear against a spring-controlled bar 5 which is slidingly mounted in brackets 6 which support the bar 5. Spiral springs 20 are attached to the bar 5 and to downwardly projecting flanges 22, and when the slabs are being rotated the corners of the blocks 23 will press against the sliding bar 5, which will yield sufficiently to allow the blocks 23 to turn, and the springs 20 will cause the 85 bar 5 to press back against the faces of the blocks 23 with sufficient force to prevent displacement of the slabs 7 during a period for the display advertising. It is apparent that the shaft 10 will be turning all the time, 90 but on account of the mutilated gearings 9 and 11 the shafts 8 will be rotated periodically and at predetermined lengths of time.

The slab 7 may be constructed with upright metallic slabs 25' attached to base or 100 end-pieces 26', and transparent plates 26 of glass or other material are attached to the slabs or bars 25. The slabs or bars 25 may be formed into mirrors or reflecting surfaces and lamps 27 placed in the angle between the bars to produce light to be reflected by the mirrors through the transparent plates 26.

The advertising matter may be written or printed across the faces of the rotatable 110

slabs, and the slabs must have uniform numbers of faces and provision is made for exposing corresponding faces of all the slabs at the same time and uniformly so that the 5 advertising matter may be read without break across the faces of the slabs.

What I claim is:—

1. An advertising machine comprising a frame, a plurality of slabs journaled in said 10 frame and each slab having a plurality of faces, check blocks rigid with the shafts of said slabs and having a corresponding number of faces, a sliding bar resting yieldingly against said blocks for holding said slabs 15 stationary for predetermined periods of time, and mutilated gearing for rotating said slabs.
2. An advertising machine comprising a frame, a plurality of slabs journaled in 20 said frame and each slab having a plurality of faces, check blocks rigid with the shafts of said slabs and having corresponding numbers of faces, a sliding bar resting yieldingly against said blocks for holding 25 said slabs stationary for predetermined periods of time, brackets attached to said frame for supporting said bar, springs for restoring said bar to normal position, and mutilated gearing for rotating said slabs.
3. An advertising machine comprising a frame, a plurality of slabs journaled in 30

said frame, and each slab having a plurality of faces, check blocks rigid with the shafts of said slabs and having corresponding numbers of faces, a sliding bar resting 35 yieldingly against said blocks for holding said slabs stationary for predetermined periods of time, brackets attached to said frame for supporting said bar, springs for restoring said bar to normal position, mutilated gearing for rotating said slabs, and a 40 casing inclosing all of said operating mechanism and provided with an opening for exposure of the faces of said slabs.

4. An advertising machine comprising a 45 supporting frame, a quadrangular frame mounted thereon, a series of slabs each having a plurality of faces and provided with shafts journaled in said frames and projecting therethrough at their lower ends, 50 mutilated gearing for rotating said shafts periodically, blocks having numbers of faces corresponding to the faces of said slabs mounted rigidly on said shafts, a sliding block bearing against said blocks, brackets 55 attached to said frame, and springs attached to said brackets and to said bar for holding the same yieldingly against said blocks and for restoring the slabs to starting position.

In testimony whereof, I set my hand this 60
25th day of March, 1916.

JOHN B. BARNETT.
